UNITED STATES PATENT OFFICE.

JULIUS J. TISHLER, OF PORT CHESTER, NEW YORK.

ENVELOP.

No. 926,624.

Specification of Letters Patent.

Patented June 29, 1909.

Application filed October 12, 1907, Serial No. 397,178. Renewed February 2, 1909. Serial No. 475,693.

To all whom it may concern:

Be it known that I, JULIUS J. TISHLER, a citizen of the United States, residing at Port Chester, in the county of Westchester, State of New York, have invented certain new and useful Improvements in Envelops; and I do hereby declare the following to be a full, clear, and exact description of the invention, such as will enable others skilled in the art to 10 which it appertains to make and use the same.

This invention relates to new and useful improvements in envelopes and it has more particular reference to a safety envelop constructed with the purpose of preventing fraudulent manipulation, opening or tampering with during its transmission through the mail.

In connection with an envelop of the above 20 type, the invention aims as a primary object to provide a novel construction, combination and arrangement of features, to constitute as an entirety, a novel sealing device.

The details of construction will appear in 25 the course of the following description, in which reference is had to the accompanying drawings, forming a part of this specification, like characters of reference designating similar parts, throughout the several views, 30 wherein:—

Figure 1 is a plan view of the blank from 35 which the present envelop is formed. Fig. 2 is a plan view showing the blank partly folded. Fig. 3 is a rear elevation showing the envelop sealed. Fig. 4 is a section on the line 4—4 of Fig. 3.

In the accompanying drawings, the envelop blank is shown as comprising a body 5, an upper flap 6, a lower flap 7 and side flaps 40 8 and 9. The flap 9 is constructed with a tongue 10 projecting at right angles centrally from its upper edge and foldable upon the inner face of said flap 9 along a line of scoring 11. The flap 9 is provided at a 45 slight distance from its upper edge with a slotted opening 12 through which the tongue 10 is passed after having been folded, the material between the line of scoring 11, and the opening 12 constituting a web 13 which 50 overlies said tongue in the folded relation of the latter. The tongue 10 in its folded relation has its outer or exposed face preferably gummed as at 14. The side flap 8 is constructed with a longitudinal slit 15 and the 55 lower flap 7 is constructed with a longitudi-

nal slit 16, which, in the folded relation of the parts is coextensive and coincident with the slit 15. The upper flap 6 is formed centrally thereof with a projecting tongue 17 having its inner face gummed as at 18. 60

In using the envelop, the flap 9 is folded upon the body 5, the flap 8 is folded upon the flap 9, and the flap 7 is folded upon the flap 8, it being understood that the tongue 10 has been previously folded upon the line 65 of scoring 11 with its end portion inserted through the opening 12.

It is preferred to form the material struck out from the opening 12 as an auxiliary flap 10', which is folded upon the outer face of the flap 9 along the lower edge of said opening 12 and which is gummed to adhere to the tongue 10 in the folded relation of the latter. When the parts have been thus assembled, the letter or other matter to be mailed is placed in 70 the pocket formed by the body 5 and the several flaps folded thereupon and the flap 6 is then folded upon the flap 7 in which operation, the gummed surface 18 of the flap 17 having been previously moistened, the flap 75 17 is inserted inwardly through the slits 16 and 15 in their coincident relation, until the end portion thereof overlaps the end portion of the flap 10, the gumming 18 causing the 80 end portions of said respective flaps 17 and 10 to adhere to one another. It will thus be seen that any attempt to open the envelop will result in mutilating the same so that the attempt will be immediately discovered. Such mutilation will readily occur by virtue 85 of the provision of the weakened web portion 13, the confines of which are indicated by dotted lines, and by virtue of the sealing of the flaps 10 and 10' to one another as well as of the sealing of the flaps 17 and 10 to one 90 another, and of the engagement of the flaps 17 through the slits 16 and 15. 95

The invention is simple in its structural details, inexpensive to manufacture, and practical and efficient in use. 100

What is claimed is:

An envelop of the type set forth, comprising a body portion provided with side flaps, an upper flap and a lower flap, one of said side flaps having formed centrally thereof and projecting from its upper edge a tongue and having at some distance below said upper edge and in a line with said tongue, a slotted opening, said tongue being foldable upon the inner face of the side flap by which 105 110

it is carried and being formed for insertion through said slotted opening, the other side flap and the lower flap being foldable upon said first named side flap and being formed

5 with coincident slits, the upper flap being formed with a projecting tongue having its inner face gummed, said last named tongue being formed for insertion through said slits in their coincident relation and being de-

signed to overlap and to be sealed to the projecting end portion of said first named tongue. 10

In testimony whereof, I affix my signature, in presence of two witnesses.

JULIUS J. TISHLER.
